UNITED STATES PATENT OFFICE.

EMIL GRIMSRUD, OF ANTELOPE, MONTANA.

PLOW.

1,253,961.

Specification of Letters Patent. Patented Jan. 15, 1918.

Application filed May 29, 1917. Serial No. 171,728.

To all whom it may concern:

Be it known that I, EMIL GRIMSRUD, a citizen of the United States, residing at Antelope, in the county of Sheridan and State of Montana, have invented certain new and useful Improvements in Plows, of which the following is a specification.

My invention relates to improvements in plows, and it consists in the constructions, 10 combinations, and arrangements herein described and claimed.

An object of my invention is to provide a plow adapted for use more particularly with a tractor, and the plow consists essentially of a collapsible stock and a suitably arranged trip lever for normally holding the collapsible stock in position on the plow beam, the purpose of the collapsible stock being to permit it to yield when an immovable 20 obstruction is encountered on the field.

Another object of the invention is to provide a plow of the character described having a spring or other suitable equivalent therefor whereby the collapsible stock may 25 be retrieved or returned to its normal operative position when an obstruction is encountered and passed.

Another object of the invention is to provide a plow of the character described, 30 which embodies a novel form of trip lever adapted more particularly for use in connection with the heel of the collapsible stock of the plow.

Other objects and advantages will appear 35 from the following specification, reference being had to the accompanying drawings, in which:—

Figure 1 is a side elevation of a plow 40 illustrating the principles of my invention, the plow being shown connected to the draw bar of a tractor.

Fig. 2 is an enlarged side elevation of a portion of the plow shown in Fig. 1, one side of the bifurcated plow being broken 45 away to reveal the trip lever and its correlated trip devices.

Fig. 3 is a view similar to Fig. 2, the parts being shown in the positions assumed 50 when the collapsible stock encounters an obstruction.

Figs. 4 and 5 are sections on the lines 4—4 and 5—5 respectively, of Fig. 1, and

Fig. 6 is a vertical section on the line 6—6 of Fig. 1.

55 In carrying out my invention, I provide a

plow beam 1 which is provided with a clevis 2 whereby the plow beam is adjustably attached to the draw bar 3 of a tractor through the medium of the bolt 4. The plow beam 1 is bifurcated in order to provide a space or 60 chamber 5 in which the collapsible plow stock 6 is fulcrumed.

The collapsible plow stock 6 is fulcrumed on a bolt 7. A heel 8 which is formed as an extension of the collapsible stock 6, is provided with a notch 9 which receives a transversely disposed bolt 10. The engagement of the bolt 10 with the notch 9 limits the upward movement of the collapsible stock 6. The heel 8 has a toe 11 which has a slit 12 70 for receiving the heel of a trip 13. The slit 12 merges with a recess 14 into which the nose 15 of a trip lever 16 enters.

A retrieving spring 17 is coiled about a bolt 18 which is fulcrumed in the heel 8 75 of the stock 6. The bolt 18 passes through a guide 19 on which the lower end of the spring 17 bears. The upper end of the spring 17 bears against the head of the bolt 18 and it will be readily apparent in Figs. 80 2 and 3, that the retrieving spring 17 will tend to normally keep the stock 6 in the position shown in Fig. 2. The guide 19 bridges the chamber or space 5 and is secured to the bifurcation of the plow beam 1. 85

A plow share 20 is secured to the lower end of the collapsible stock, bolt holes 21 and 21^a being formed in the stock so that bolts may be passed through to secure the share in place. 90

It will be observed that the other hole 21^a is elongated in the form of a slot. The purpose of the slot 21^a is to provide a certain amount of movement for the adjustment of the plow share 20. For the purpose of adjustment, the plow share 20 has a lug shown in Fig. 1, through which an adjusting screw passes and engages the rear surface of the collapsible stock 6. A bolt passes through the stock and the slot 21^a, and when tightened, securely holds the plow shaft 20 in its 95 adjusted position.

A pair of alining abutment openings 22 is formed in the bifurcated sides of the plow beam 1. Each of the abutment openings 100 22 is of a peculiar shape in that a rounded end 23 is provided which merges at the bottom with a pair of abutment steps 24. The bottom of each of the openings 22, is substantially straight between the curved por- 105 110

23 and the first abutment step 24. The upper step 24 terminates at a recess 25 from which the straight portion at the top of the opening 22 extends and completes the opening.

5 It will be observed that each opening 22 is widened at the place adjacent to the steps 24, the provision thus gained permitting sufficient latitude of movement of an abutment 26 formed on each side of the trip lever 16. Under normal conditions, the trip lever 16 assumes a substantially perpendicular position with respect to the plow beam 1. This position is illustrated in Figs. 1 10 and 2, wherein it will be seen that the recessed end of each of the abutments 26 is superposed on the first of the steps 24. It will also be observed that the opposite end of each of the abutments 26 is round and 15 rests in the rounded portion 23 of the abutment opening 22. The rounded end of the abutment 26 acts as a fulcrum for the trip lever 16 when the collapsible stock 6 is moved from its normal position with respect 20 to the plow beam 1, when an obstruction is encountered on the field.

30 The recess in the end of the abutments 26 extends completely across the lower end of the trip lever 16, and a wedge-shaped opening 27 is formed centrally of the recess referred to. The pivot head 28 of a tension staff 29 occupies the wedge-shaped opening 27. The pivot head 28 remains in position in the opening 27 by the pressure of a spring 30 on the staff 29. One end of the spring 30 bears against a screw-eye 31 on the staff 29, and the other end bears against an arm 32 which is dependent from a dog 33.

40 The pressure of the spring 30 against the screw-eye 31 keeps the pivot head 28 in engagement with the wedge-shaped opening 27. It will be seen that the pivot head 28 is narrower than the opening 27 is deep. This is illustrated in Figs. 2 and 3 wherein 45 by comparison of the different positions of the trip lever 16, it will be understood that the lever 16 and the pivot head 28 have slight relatively pivotal movement.

50 A chamber 34 is formed at the lower end of the trip lever 16. The trip 13 is fulcrumed in the chamber 34 on the pin 35. A spring 36 connected to the screw-eye 31 and the extremity of the long end of the trip 13, keeps the heel of the trip 13 projected beyond the rear edge of the trip lever 16 so that it may be engaged by a slit 12 in the toe 11 of the stock 6.

60 A pawl 37 is fulcrumed on the extremity of the long end of the trip 13. The pawl 37 moves in a groove 38 which is an extension of the chamber 34. The lateral edges of the trip lever 16 are notched at 39 to receive the claws 40 of the dog 33. The upper end of the pawl 37 is tapered to a point and is

adapted to keep the claws 40 of the dog 33 65 out of engagement with the notches 39 when the collapsible stock 6 is in the normal position shown in Figs. 1 and 2.

The lower claw 40 projects beside the pawl 37 as indicated at 40^a to bear against 70 the trip lever, as shown in Fig. 2. The purpose of the pawl 37 is to act upon the dog 33 and keep the claws 40 out of the notches 39. This is accomplished through the movement of the trip 13 when it is engaged by the 75 toe 11. The movement of the trip 13 shoves the pawl 37 upwardly in its groove 38 so that the base and the point of the tapered portion of the pawl strike the lower and upper claws 40 at the same time and move the 80 dog outwardly away from the trip lever 16. The spring 30 on the tension staff 29 serves the double function of keeping the pivot head 28 in place in the opening 27, and also urging the claws 40 of the dog 33 toward the 85 trip lever 16. This will be obvious since it can readily be seen that the pivotal mounting of the dog 33 on the bolt 33^a will permit the action described.

A spring 41 is connected at one end to a 90 hook 42 on the upper end of the trip lever 16. The other end of the spring is connected to a similar hook on a fixed part of the plow beam. The spring 41 keeps the trip lever 16 in its vertical position by pressing the abutments 26 against the bottoms of the abutment openings 22. The round parts of the openings and the abutments make it possible that the spring 41 will do this.

95 The plow stock 6 may be collapsed by 100 manual efforts through the medium of a lever 43 and a link 44 connected between the lever and the trip lever 16. The lever 43 is mounted on the platform 45 of the tractor and when the operator knows that an obstruction is being approached, he may if it be desired, pull upon the lever 43 when the trip lever 16 will be operated to release the collapsible stock 6 in a manner which will 105 presently be more fully understood. The 110 lever 43 is locked to its adjustment by the usual quadrant and detent connections, and in order to permit freedom of movement of the trip lever 16 when an obstruction is encountered on the field, the end of the link 44 115 is flattened and provided with a slot 44^a which receives the securing pin on the lever 43. Ordinarily the pin occupies the upper end of the slot 44 and obviously when the trip lever 16 moves, the link 44 will simply 120 ride over the pin.

125 The operation of the device is as follows. The plow beam 1 is one of a number which are attached to the draft bar 3 which in actual practice extends diagonally beneath the tractor platform 45. Under normal conditions, the trip lever 16 is perpendicular with respect to the plow beam 1. By refer-

ence more particularly to Fig. 2, it will be seen that the nose 15 of the trip lever 16 rests in the notch 14 in the toe 11 of the stock 6. The heel of the trip 13 is also disposed in the 5 slit 12 which is located so that it acts as a depressor for the heel of the trip 13. The front end of the trip 13 is thus elevated and tension is stored in the spring 36. The pawl 37 is accordingly elevated and the 10 claws 40 of the dog 33 are forced away from the notches 39 in the trip lever 16.

The nose 15 of the trip lever 16 forms the sole support for the collapsible plow stock 6 and in actual practice will be made heavy 15 enough to withstand the strains imposed thereon by the plow in moving through the soil. The trip lever 16 is prevented from rocking on the fulcrums formed by the rounded portions of the abutments 26 and 20 the openings 22, by the spring 41 which is strong enough to prevent the dislodgment of the end of the abutment from the first step 24.

Should an obstruction be now encountered 25 on the field which is so great that it cannot be moved by the plow share 20, the rapidly increasing strain of the toe 11 on the nose 15 of the lever 16 will overcome the tension of the spring 41 and cause the latter to rock 30 upon its fulcrum.

The trip lever 16 will then tilt to the position shown in Fig. 3 wherein the recess in the abutments 26 is out of registration or engagement with the first step 24 and consequently freedom of movement of the lever 16 is permitted when the toe 11 strikes the nose 15 when the collapsible stock 6 returns to its former position. It will be understood that the trip lever 16 is tilted to the 40 position shown in Fig. 3, by the downward movement of the toe 11 when the obstruction on the field above referred to strikes the point of the share 20.

The claws 40 engage the notches 39 in the 45 front edge of the lever 16 when the lever is tilted to the position shown in Fig. 3. The lever is thus held in this position. The tapered portion of the pawl 37 is in such a position relatively to the claws 40, that the claws will be quickly disengaged from the notches 39 upon upward movement of the pawl.

When the obstruction in the field is overcome or passed, the retrieving spring 17 exerts its influence on the stock 6 and pulls it back to its original position. When this occurs the toe 11 of the heel 8 will first strike the nose 15 and slightly displace the trip lever 16. In this instance, the claws 40 in 50 the notches 39 act as a fulcrum for the lever 16 and the displacement of the lever 16 occurs at the lower end and against the tension of the spring 30 on the tension staff 29. As soon as the nose 15 is passed by the toe 11,

the lever 16 swings back to its former position with the round parts of the abutments 26 in the similarly rounded portions of the openings 22.

The heel of the trip 13 is engaged in turn by the toe 11, and as the high part of the toe 11 rides over the heel of the trip 13 just previously to the slipping of the heel into the slit 12, the trip 13 will be rocked on its fulcrum 35 with the result that the front end will be elevated. When the front end of the 75 trip 13 is elevated, the pawl 37 is consequently slid upwardly so that the claws 40 are disengaged from the notches 39. The spring 41 will then pull the upper end of the lever 16 upwardly so that the lever 16 finally assumes the position shown in Figs. 1 and 2.

The obvious advantage of a plow having a collapsible stock as illustrated in the drawings, is that no attention need be paid to 85 obstructions in the field. The use of tractors to draw great numbers of plows across a field has made the provision of an automatically operated device for overcoming obstructions on the field, necessary. The 90 breaking of a plow stock when the plow encounters a rock or snag on the field, is not an infrequent occurrence. When a plow stock is thus broken, much time is necessary 95 in making repairs. An expedient commonly used to overcome the breakage of the plow stock, is to mount the stock on the beam in such a manner that it may be held in place by a soft metal pin. The purpose of the pin is to permit the plow stock to swing 100 after the pin is sheared by reason of the the encountering of an obstruction by the plow.

In either event considerable time is lost and it is the purpose of the present invention to obviate the necessity of stopping 105 for repairs by providing an automatically collapsible plow stock which is perfectly rigid under normal conditions but will yield when an obstruction is encountered.

While the construction and arrangement 110 of the device as illustrated in the drawings, is that of a generally preferred form, obviously modifications and changes therein may be made without departing from the 115 spirit of the invention or the scope of the claims.

I claim:—

1. A plow beam, a plow stock fulcrumed on the beam the plow stock having a heel, a trip lever having a nose engageable with the heel, a holding spring connected to the trip lever the spring being adapted to be overcome when the plow stock encounters an obstruction, a normally inactive dog adapted 120 to engage and hold the trip lever subsequently to the displacement of the trip lever when the stock strikes an obstruction, and 125

means mounted on the trip lever engageable upon the return of the plow stock for releasing the trip lever from the dog.

2. A plow beam provided with openings 5 having round ends and steps, a plow stock fulcrumed on the plow beam the stock having a heel, a trip lever having a nose engageable with the heel, abutments on the trip lever, the abutments having round ends for 10 pivotally engaging the round ends of the openings, recessed ends for engaging the steps, and means for keeping the round ends of the abutments in the round portions of the openings.

15 3. A plow beam provided with an opening having a round end and a step, a plow stock fulcrumed on the beam the stock having a heel, a trip lever having an abutment resting in the opening, the abutment having a recess, 20 said abutment having a round end for pivotal connection with the round portion of the opening, a nose on the trip lever engageable with the heel, a tension staff having a pivot located in the recess, and resilient 25 means on the tension staff for urging the abutment into pivotal connection with the rounded end of the opening.

4. A plow beam having an opening, a plow stock fulcrumed on the beam, a trip 30 lever having a nose engageable with the stock, a fulcrum-abutment on the trip lever, the fulcrum abutment being receivable in the opening in the plow beam, a tension staff having a pivot head for engaging the abutment, and a spring on the tension staff for 35 urging the fulcrum-abutment into position in the opening in the plow beam.

5. The combination with the plow beam, 40 of a trip lever having a pivotal mounting on the beam, a plow stock adapted to displace the trip lever upon the encounter of an obstruction, a dog for holding the trip lever in its displaced position, and a trip carried by the trip lever and actuated upon the return 45 of the stock for releasing the trip lever from the dog.

6. The combination with a plow beam, of 50 a trip lever having a pivotal mounting on the beam, a plow stock adapted to displace the trip lever upon the encounter of an obstruction, a dog for holding the trip lever in its displaced position, a trip carried by the trip lever engageable by the stock upon the return of the stock to a normal position, and 55 a pawl carried by the trip for releasing the trip lever from the dog.

7. The combination with a plow beam, of 60 a trip lever having a pivotal mounting on the beam, a plow stock adapted to displace the trip lever upon the encounter of an obstruction, a dog for holding the trip lever in its displaced position, a trip carried by the trip lever engageable by the stock upon the return of the stock to a normal position, a 65 pawl carried by the trip for releasing the

trip lever from the dog, and means for holding the pawl in a normally inactive position.

8. The combination with the plow beam, 70 of a trip lever having pivotal connection therewith, the lever having a chamber and a groove, a plow stock fulcrumed on the beam and adapted to displace the trip lever upon the encounter of an obstruction, a dog having claws for engaging and holding the trip lever in the displaced position, a trip pivoted 75 in the chamber engageable upon return of the stock, and a pawl joined with the trip and slid able in the groove for disengaging the trip lever from the claws of the dog.

9. The combination with a plow beam, of 80 a trip lever having a pivotal connection therewith, the lever having a chamber and a groove, a plow stock fulcrumed on the beam and adapted to displace the trip lever upon the encounter of an obstruction, a dog having 85 claws for engaging and holding the trip lever in the displaced position, a trip pivoted in the chamber engageable upon return of the stock, a pawl joined with the trip and slid able in the groove for disengaging the trip lever from the claws of the dog, and resilient means for restoring the trip lever to the former position upon release thereof from the claws.

10. The combination with the plow beam, 90 of a trip lever having a nose and a notch, a plow stock sustained by the nose and adapted to displace the trip lever on the encounter of an obstruction by the plow stock, a dog engageable with the notch when the trip lever is displaced, a trip fulcrumed on the trip lever engageable by the plow stock when in the normally sustained position, and a pawl carried by the trip in engagement with the dog for holding the dog from 100 engagement with the notch.

11. The combination with the plow beam, 110 of a trip lever having a nose and a notch, a plow stock sustained by the nose and adapted to displace the trip lever on the encounter of an obstruction by the plow stock, a dog engageable with the notch when the trip lever is displaced, a trip fulcrumed on the trip lever engageable by the plow stock when in the normally sustained position, a 115 pawl carried by the trip in engagement with the dog for holding the dog from engagement with the notch, and a resilient element jointed with the trip for retracting the pawl from the dog when the stock encounters an 120 obstruction and the trip lever is displaced.

12. A plow beam, a collapsible stock fulcrumed on the beam, a step formed on the beam, a trip lever for sustaining the stock, the trip lever being fulcrumed adjacent to 125 the step and normally having engagement therewith, the trip being moved from engagement with the step upon collapse of the stock, a tension staff having a resilient element for holding the trip lever on the ful- 130

crum, and a dog adapted to engage and hold the trip lever from the step upon collapse of the stock.

13. In a plow having a beam, the combination with a dog having an arm, a plow stock fulcrumed on the beam and being susceptible to collapse, a stock sustaining lever adapted to assume a tilted position upon collapse of the stock, and a tension staff having a resilient element engaged with and disposed between the stock sustaining lever and the arm whereby the stock sustaining lever is held on its fulcrum.

14. A plow beam, a stock fulcrumed on the beam, the stock having a heel, a trip lever having a nose for engaging the heel and sustaining the stock from collapse, said trip lever being adapted to assume a tilted position upon the collapse of the stock, means for holding the lever in its tilted position, and resilient means connected with the trip lever for permitting the heel to snap past the nose upon the return of the stock.

15. A plow beam, a stock fulcrumed on the beam, the stock having a heel, a trip lever having a nose for engaging the heel and sustaining the stock from collapse, said trip lever being adapted to assume a tilted position upon the collapse of the stock, means for holding the lever in its tilted position, resilient means connected with the trip lever for permitting the heel to snap past the nose upon the return of the stock, and means for automatically returning the stock.

16. A plow beam, a stock fulcrumed on the beam, the stock having a heel, a trip lever having a nose for engaging the heel and sustaining the stock from collapse, said trip lever being adapted to assume a tilted position upon the collapse of the stock, means for holding the lever in its tilted position, resilient means connected with the trip lever for permitting the heel to snap past the nose upon the return of the stock, means for automatically returning the stock, and means for automatically releasing the lever holding means.

17. A plow beam, a stock fulcrumed on the beam, a stock having a heel, a trip lever

having a nose for engaging the heel and sustaining the stock from collapse, said trip lever being adapted to assume a tilted position upon the collapse of the stock, means for holding the lever in its tilted position, and a pivot head yieldably retaining said trip lever in a set position at its lower end, whereby said heel may snap past said nose upon the return of the stock, and means for automatically returning the stock.

18. A plow beam, a stock fulcrumed on said beam, said stock having a heel, a trip lever having a nose for engaging said heel and retaining said stock in a releasable set position, said trip lever being adapted to assume a tilted position upon the collapse of the stock, means for holding the said lever in its tilted position, said lever having an opening formed adjacent its lower end, a pivot head extending into said opening, a spring pressed shaft engaging said pivot head, thereby yieldably retaining the lower end of said lever in a set position, whereby said heel may snap past said nose upon the return of the stock, and means for automatically returning the stock.

19. A plow beam, a stock fulcrumed on said beam, said stock having a heel, a trip lever having a nose for engaging said heel and retaining said stock from collapse, said trip lever being adapted to assume a tilted position upon the collapse of the said stock, a dog for holding said lever in its tilted position, an arm projecting from said dog, said trip lever having an opening formed adjacent its lower end, a pivot head extending into said opening, a shaft connected to said pivot head and projecting through said arm, a spring carried by said shaft and urging said head and arm in opposite directions, whereby the lower end of said lever will be yieldably retained in a set position, thereby permitting said heel to snap past the said nose upon the return of the stock, and means for automatically returning the said stock.

In testimony whereof I affix my signature in presence of two witnesses.

EMIL GRIMSRUD.
